Callaway Mills, La Grange, Ga., a corporation
of Georgia

Application May 1, 1945, Serial No. 591,266

18 Claims. (Cl. 139—55)

1

This invention relates to looms in which warp yarns are manipulated by discs or cards to form sheds in which filling yarn is inserted to produce a fabric. More particularly, the invention is concerned with a novel mechanism by which the discs of such a loom may be rotated in one direction or the other under the control of a pattern element. In a loom in which the new disc drive is employed, it is not necessary to provide means for twisting together the strands of warp yarn which are to be handled by a single disc and the warp yarns may, accordingly, be supplied to the discs from a beam or any other suitable source.

In disc looms in which the discs continuously rotate in one direction, the strands of warp yarn handled by a single disc are twisted together by the rotation of the disc, and the twist runs in both directions from the disc. If measures were not taken to prevent, the twist running back from each disc to the supplies of warp yarns would soon make it impossible to draw the yarns from the supplies. It has, accordingly, been proposed to reverse the direction of rotation of the discs periodically so that the discs rotate one or more steps in one direction and then rotate stepwise in the reverse direction, the reverse rotation of the discs taking out the twist imparted to the groups of warp yarns handled by individual discs, between the discs and the warp yarn supplies. The mechanism heretofore proposed for the purpose of driving the discs with a reversing action is impractical, in that the discs are not under positive control at all times and part of their movement results from momentum.

The new mechanism overcomes the objections to the disc drive previously proposed and it includes positive means for rotating the discs in one direction or the other. The disc rotating means may include a shaft operatively connected to the discs, and pawl and ratchet means for moving the shaft stepwise in one direction or the other under the control of means which are in turn controlled by a pattern element. Means, preferably taking the form of a shaft carrying cams, are provided for operating the pawl and ratchet means and for advancing the pattern element, and in the preferred construction, the disc drive shaft is provided with a brake which is actuated by the cam shaft at the appropriate times to hold the disc drive shaft against accidental rotation.

For a better understanding of the invention, reference may be made to the accompanying drawings, in which

Fig. 1 is a view in side elevation of a disc loom equipped with the new disc drive, parts of the loom being broken away to show the features of the drive;

Fig. 2 is a view in rear elevation, with parts

2

broken away, of lower portions of the new drive;

Fig. 3 is a view similar to Fig. 2, showing upper portions of the new drive;

Fig. 4 is a sectional view, the lower part being taken on the line 4—4 of Fig. 2, and the upper part on the line 4a—4a of Fig. 3;

Fig. 5 is a vertical sectional view, the lower part being taken on the line 5—5 of Fig. 2, and the upper part on the line 5a—5a of Fig. 3;

Fig. 6 is a vertical sectional view on the line 6—6 of Fig. 2;

Fig. 7 is a sectional view on the line 7—7 of Fig. 3;

Fig. 8 is a view in end elevation of a ratchet wheel used in the new drive;

Fig. 9 is a view in end elevation of a modified drive;

Fig. 10 is a plan view of the construction shown in Fig. 9; and

Fig. 11 is a view in rear elevation of the construction shown in Fig. 9.

The loom illustrated in Fig. 1 comprises the usual sides 20, between which extends a crank shaft 21 operating a lay 22 provided with a reed 23. A shuttle 24 is movable across the lay in the usual way by conventional means, such as picker sticks, etc., operated from cam shaft 25. The warp yarns 26 are drawn from any suitable source of supply, such as beam 27, the arbor 28 of which is provided with a brake drum 28a acted on by a brake band 29. From the beam, the yarns travel through a device, generally designated 30, for maintaining the yarns under tension, the device preferably being that disclosed and claimed in my co-pending application Serial No. 591,265, filed May 1, 1945. From the tension control device, the yarns pass around lease rods indicated at 31, and thence to discs 32. In the construction shown, each disc has four openings for the passage of individual yarns, and the discs are formed with peripheral teeth (not shown) meshing with long pinions on upper and lower shafts 33, 34, respectively, which are supported in upward extensions 35 on the loom sides. The discs may be held in spaced relation by any suitable means, such as those shown in my co-pending application Serial No. 591,267, filed May 1, 1945.

In the operation of the loom, the discs are rotated stepwise through a quarter turn at each step, and sheds are thereby formed, through which shuttle 24 is passed to produce a fabric. The fabric is taken up on a take-up roll 36 after having passed around other rolls, such as that indicated at 37.

The new drive for the discs comprises a shaft 38 mounted in suitable bearings in the loom sides and provided with a sprocket wheel 39, about which is trained a chain 40 similarly trained about a sprocket wheel on shaft 34. Shafts 33 and 34 are connected by a chain 41 trained about

sprocket wheels thereon, so that the shafts will rotate in unison. Shaft 38 is provided with a pair of ratchet wheels 42, 43 fast thereon and oppositely disposed; that is, having their teeth extending in opposite directions. A yoke 44 straddles shaft 38 and is pivotally supported at 45 on an arm 46 pivoted at 47 on an upright frame member 48 attached to a part of the loom framework. The yoke is provided with pawls for operating the ratchet wheels and, in the construction shown, the pawls take the form of pins 49, 50 engageable with the teeth of ratchet wheels 42, 43, respectively, depending on the position of yoke 44. A spring 51 connected to the tail of the yoke and to frame member 48 tends to swing the yoke counterclockwise on its pivot 45 to bring pin 49 into operative relation to the teeth of ratchet 42. The yoke is movable to the opposite position, as shown in Fig. 4, by means controlled by a pattern device.

The pattern device includes a pattern element 52 in the form of a chain carrying riders 53 mounted in a selected arrangement on the links thereof, and the chain runs over a sprocket wheel 54 on a shaft 55 supported in bearings in arms 56 attached to the arch 57 of the loom. A ratchet wheel 58 fast on shaft 55, is actuated by pawl 59 carried by an arm 60 loosely mounted on shaft 55 and connected by a rod 61 to an arm 62 pivoted at 63 on a bracket 64 attached to the loom frame. Arm 62 is swung up and down by a cam 65 on the loom cam shaft 25, and each time the arm is raised, pawl 59 engages ratchet wheel 58 by one tooth and advances shaft 55 by one step. Shaft 55 carries a disc 66 fast thereon, the disc having peripheral depressions 66a which may be entered by a disc 67 carried by an arm 68 pivotally mounted on a rod 56a extending between arms 56. The free end of arm 68 is connected by a spring 69 to one end of a rod 70 mounted for swinging movement on shaft 55 and having a rearward extension overlying rod 56a. With this arrangement, arm 70 acts as a stop for one end of spring 69, and, as shaft 55 is advanced a step by rotation of ratchet wheel 58, disc 67 is forced upwardly out of a depression in the periphery of disc 66 against the action of spring 69. Disc 67 then enters the next depression in disc 66 and this serves to hold shaft 55 against further movement until ratchet wheel 58 is advanced another step.

The pattern element 52 controls the position of yoke 44 by means of an arm 71 pivotally mounted on rod 56a. Arm 71 overlies the pattern element and is engageable by the riders 53 thereon, whenever a rider lies at the top of sprocket wheel 54 (Fig. 4). The free end 72 of arm 71 is offset from the remainder of the arm and is connected by a rod 73 to a crank arm 74 fast on a shaft 75 mounted in a bracket on one of the loom sides, and shaft 75 is provided with another arm 76 connected by a link 77 and a stiff spring 78 to one leg of yoke 44. With this arrangement, when a rider 53 on chain 52 lies beneath arm 71, the arm is raised, and this causes shaft 75 to be swung clockwise. Arm 76 then acts through link 77 and spring 78 to pull the lower end of yoke 44 to the left, as shown in Fig. 4. In this position of the yoke, pin 50 lies in operative relation to the teeth of its ratchet wheel 43, and upon raising of the yoke by arm 46, the pin acts on the ratchet wheel to rotate the wheel and shaft 38 by one tooth on the wheel. Arm 46 is regularly raised and lowered during the operation of the loom by means of a double acting

cam 79 on shaft 25, the cam engaging a roller 80 mounted on a stud on arm 46.

In order to prevent overrunning of shaft 38, it is provided with a brake drum 81 having a peripheral channel in which is seated a brake band consisting of a strap 82 carrying a length of brake lining 83 on its inner face. The strap is connected at one end to a pin 84 on an arm 85, pivotally mounted at 86 on a bracket 87 secured to the loom frame. The other end of the strap is connected to a bolt 88, which passes through openings in arm 85 and carries a wing nut 89, beneath which is a spring 90 encircling the bolt and bearing at one end against the wing nut and at the other end against arm 85. Arm 85 is raised and lowered during the operation of the loom by a double acting cam 91 on shaft 25. When a low part of the cam is in contact with arm 85, the strap 82 bears lightly against the drum 81, so that shaft 38 can be moved against the action of the brake. When a high point on cam 91 bears against the arm and swings it upwardly, strap 82 bears so tightly against drum 81 as to prevent rotation of shaft 38.

In the operation of the apparatus so far described, the rotation of cam shaft 25 causes yoke 44 to be raised and lowered twice per revolution of the shaft. In each upward movement of the yoke, one or the other of pins 49, 50 engages its respective ratchet wheel 42, 43 and rotates the wheel and shaft 38 by one tooth. During such movements of shaft 38, arm 85 is in the down position so that the brake band 82 bears lightly against drum 81 and permits the shaft to be rotated. In the end of each step in the movement of shaft 38, arm 85 is raised to apply the brake and prevent any overrunning of shaft 38. Once per revolution of shaft 25, arm 62 is operated to advance ratchet wheel 58 by one tooth. This causes shaft 55 and sprocket wheel 54 to be rotated a step and pattern chain 52 to be advanced a step.

Arm 71 overhangs pattern chain 52, and whenever a rider 53 on the chain engages arm 71, the arm is maintained in the raised position shown in Fig. 4 and operates through the connections described to keep the lower end of yoke 44 to the left, as shown in Fig. 4. With the yoke in this position, the raising of arm 46 by cam 79 causes pin 50 to engage a tooth of its ratchet wheel and advance the wheel by one tooth for each raising of arm 46. This causes shaft 38 to be advanced counterclockwise by one step, and the shaft acts through chain 40 to rotate shaft 34 one step. Rotation of shaft 34 causes shaft 33 to rotate, and the pinions on the shaft cause discs 32 to move one step in a clockwise direction, as viewed in Fig. 1. Whenever a portion of chain 52, not provided with a rider, comes beneath arm 71, the arm swings down, and this permits spring 51 to act on the tail of yoke 44 and swing the yoke, so that pin 49 moves into operative relation with its ratchet wheel 42. On the next upward movement of arm 46, ratchet wheel 42 is advanced one step, and this causes shaft 38 to move clockwise by one step and discs 32 are moved counterclockwise.

The brake acting on shaft 38 and consisting of brake drum 81, strap 82, and arm 85, is released just prior to each upward movement of arm 46 and yoke 44. At the end of each step in the movement of shaft 38, the brake is again applied thereto, so that the shaft is arrested and held against accidental rotation, until the next action of arm 46 and yoke 44.

In the modified construction shown in Figs. 9, 10, and 11, the crank shaft 21' of the loom carries a gear 92 meshing with gear 93 on a shaft 94. Shaft 94 is provided with a disc 94a carrying an eccentric pin to which is connected rod 95, which reciprocates a rod 96 mounted in a guide 97. Rod 96 is attached at one end to a yoke 98, in which are pivotally mounted pawls 99, each of which is provided with a pin 100 lying within a slot 101 in a bar 102. The bar is connected by a cord 103 to the harness lever 104 of a dobby head, the position of the lever being controlled by a chain 105 trained about a sprocket wheel 106 on a shaft 107 and carrying riders 108 in a selected arrangement. Pawls 99 operate on respective ratchet wheels 109, 109a on a shaft 110 provided with a sprocket wheel 111, about which is trained a chain 112. The chain passes about a sprocket wheel 113 on a shaft 34', which corresponds to shaft 34 in the Fig. 1 construction, and is provided with a long pinion (not shown), the teeth of which mesh with the teeth of the discs to be driven.

The construction shown in Figs. 9, 10, and 11 operates as follows: On each revolution of shaft 94, rod 96 is reciprocated and moves yoke 98 back and forth. Both pawls 99 move with the yoke, and one or the other of the pawls engages its respective ratchet wheel 109, 109a, depending on the position of bar 102. When a rider on chain 105 lies beneath the harness lever 104, the lever is raised and this raises bar 102. In such upward movement of bar 102, the lower end of the upper slot 101 engages pin 100 on the upper pawl 99 and raises the pawl free of ratchet wheel 109, this movement of the pawl being resisted by spring 114 connecting the pawl to the bar. At the same time, lower pawl 99 is raised by its spring 114 connecting the pawl to bar 102, and the end of the pawl moves into operative relation with the teeth on ratchet wheel 109a. On the next movement of rod 96 and yoke 98 to the left, pawl 99 causes its ratchet wheel to be advanced by one tooth, and this causes clockwise rotation of shafts 100 and 34' and counterclockwise movement of the discs driven by shaft 34'.

Shaft 107 is advanced stepwise by appropriate means, as, for example, a ratchet wheel on the shaft, similar to ratchet wheel 58, a pawl for moving the ratchet wheel, and cam means for actuating the pawl. So long as a rider 108 on the chain lies beneath lever 104 at each period of rest of the chain, bar 102 will remain elevated, and lower pawl 99 will be effective. Whenever a chain link not provided with a rider comes beneath lever 104, bar 102 is allowed to move down, and this causes upper pawl 99 to become effective and the lower pawl to become ineffective. The discs are thus rotated stepwise in one direction or the other by rotation of shaft 34', the direction of rotation of which is determined by the pattern chain.

The loom illustrated and described is provided with discs having four openings therethrough, so that each disc handles four warp yarns, or a multiple of four yarns. It is to be understood that the discs may have a number of openings other than four, if desired, or the discs shown may be operated to control only two yarns.

This application is a continuation-in-part of my application Serial No. 551,830, filed August 30, 1944.

The claims are:

1. In a loom, the combination of a plurality of warp shedding discs, means operatively connected

5 to the discs for rotating them stepwise in either direction, said means including a shaft, a pair of oppositely disposed ratchet wheels on the shaft, and a reciprocating member carrying a pair of pawls engageable selectively with respective ratchet wheels, means for continuously reciprocating said member, control means for controlling the action of the rotating means, and a pattern device for controlling the control means.

10 2. In a loom, the combination of a plurality of warp shedding discs, a shaft operatively connected to the discs for rotating them, oppositely disposed ratchet wheels on the shaft, a pair of pawls engageable selectively with respective ratchet wheels, means for reciprocating the pawls in unison, control means acting to render a selected pawl effective and the other ineffective, and a pattern device for controlling the control means.

15 3. In a loom, the combination of a plurality of warp shedding discs, means operatively connected to the discs for rotating them in either direction, control means operative only for controlling the operation of the rotating means, a pattern device for controlling the control means, and a drive shaft for operating both the rotating means and the pattern device.

20 4. In a loom, the combination of a plurality of warp shedding discs, means operatively connected to the discs for rotating them in either direction, control means operative only for controlling the operation of the rotating means, a pattern device for controlling the control means, and means including a shaft and cams thereon for operating both the rotating means and the pattern device.

25 5. In a loom, the combination of a plurality of warp shedding discs, means operatively connected to the discs for rotating them stepwise in either direction, control means operative only for controlling the operation of the rotating means, a pattern device for controlling the control means, means acting on the rotating means to arrest the rotation of the discs at the end of each step in their movement, and a drive shaft for operating the rotating means and the pattern device.

30 6. In a loom, the combination of a plurality of warp shedding discs, means operatively connected to the discs for rotating them stepwise in either direction, control means operative only for controlling the operation of the rotating means, a pattern device for controlling the control means, means acting on the rotating means to arrest the rotation of the discs at the end of each step in their movement, and means including a shaft and cams thereon for operating the rotating means and the pattern device.

35 7. In a loom, the combination of a plurality of warp shedding discs, means operatively connected to the discs for rotating them stepwise in either direction, said means including a pair of ratchet wheels and pawl means selectively operable on one or the other of the ratchet wheels, control means operative only for controlling the action of the pawl means, a pattern device for controlling the control means, and a drive shaft for operating both the rotating means and the pattern device.

40 8. In a loom, the combination of a plurality of warp shedding discs, means operatively connected to the discs for rotating them stepwise in either direction, said means including a pair of ratchet wheels and pawl means selectively operable on one or the other of the ratchet wheels,

control means operative only for controlling the action of the pawl means, a pattern device for controlling the control means, and means including a shaft and cams thereon for operating both the rotating means and the pattern device.

9. In a loom, the combination of a plurality of warp shedding discs, means operatively connected to the discs for rotating them stepwise in either direction, said means including a pair of ratchet wheels and reciprocating pawl means selectively operable on one or the other of the ratchet wheels, control means operative only for controlling the action of the pawl means, a pattern device for controlling the control means, and a drive shaft for operating both the rotating means and the pattern device.

10. In a loom, the combination of a plurality of warp shedding discs, means operatively connected to the discs for rotating them stepwise in either direction, said means including a shaft, a pair of oppositely disposed ratchet wheels on the shaft, and a reciprocating member carrying pawls engageable selectively with respective ratchet wheels, means for continuously reciprocating said member, control means for controlling the operation of the reciprocating member to select the pawl which will engage its ratchet wheel, and a pattern device for controlling the control means.

11. In a loom, the combination of a plurality of shedding discs, a shaft connected to the discs to rotate them, a pair of ratchet wheels oppositely disposed on the shaft, a yoke, a pair of pawls carried by the yoke and engageable selectively with respective ratchet wheels, means for moving the yoke between two positions to bring a selected pawl into operative relation to its ratchet wheel, means for reciprocating the yoke, pattern means for controlling the operation of the yoke moving means, and means for operating the yoke moving means and the pattern means.

12. In a loom, the combination of a plurality of warp shedding discs, means operatively connected to the discs for rotating them stepwise in either direction, control means for controlling the operation of the rotating means, a pattern device for controlling the control means, means acting on the rotating means to arrest the rotation of the discs at the end of each step in their movement, and a drive shaft for operating the rotating means, the pattern device, and the arresting means.

13. In a loom, the combination of a plurality of warp shedding discs, means operatively connected to the discs for rotating them stepwise in either direction, control means for controlling the operation of the rotating means, a pattern device for controlling the control means, means acting on the rotating means to arrest the rotation of the discs at the end of each step in their movement, and means including a shaft and cams thereon for operating the rotating means, the pattern device, and the arresting means.

14. In a loom, the combination of a plurality of warp shedding discs, a shaft operatively connected to the discs to rotate them, a pair of ratchet wheels oppositely disposed on the shaft, means including pawls selectively engageable with respective ratchet wheels to rotate the shaft stepwise in opposite directions, brake means operable on the shaft to arrest its movement at the end of each step, control means for controlling the action of the rotating means, a pattern de-

vice including a pattern element for controlling the action of the control means, and means for operating the rotating means and advancing the pattern element stepwise, said means releasing the brake means at the beginning of each operation of the rotating means.

15. In a loom, the combination of a plurality of warp shedding discs, a shaft operatively connected to the discs to rotate them, a pair of ratchet wheels oppositely disposed on the shaft, means including pawls selectively engageable with respective ratchet wheels to rotate the shaft stepwise in opposite directions, brake means operable on the shaft to arrest its movement at the end of each step, control means for controlling the action of the rotating means, a pattern device including a pattern element for controlling the action of the control means, and a shaft provided with cams for operating the rotating means, advancing the pattern element stepwise, and releasing the brake means at the beginning of each operation of the rotating means.

16. In a loom, the combination of a plurality of warp shedding discs, a shaft operatively connected to the discs to rotate them, a pair of ratchet wheels oppositely disposed on the shaft, a yoke carrying a pair of pawls engageable with respective ratchet wheels, an arm movably supporting the yoke, means connected to the yoke for shifting it relative to the arm for bringing a selected pawl into operative relation to its ratchet wheel, a pattern element, means controlled by the element for controlling the yoke shifting means, and a shaft having cams for advancing the pattern element stepwise and for moving the arm and the yoke thereon to cause the selected pawl to engage its ratchet wheel and advance the first shaft by one step.

17. In a loom, the combination of a plurality of warp shedding discs, a shaft operatively connected to the discs to rotate them, a pair of ratchet wheels oppositely disposed on the shaft, a yoke carrying a pair of pawls engageable with respective ratchet wheels, an arm movably supporting the yoke, means connected to the yoke for shifting it relative to the arm for bringing a selected pawl into operative relation to its ratchet wheel, a pattern element, means controlled by the element for controlling the yoke shifting means, a brake drum on the shaft, an arm carrying an element engageable with the brake drum to stop rotation of the shaft, and a cam shaft having cams for advancing the pattern element stepwise, for moving the yoke supporting arm to cause the selected pawl to engage its ratchet wheel and advance the first shaft by one step, and for swinging the second arm to free the element thereon from the brake drum.

18. In a loom, the combination of a plurality of warp shedding discs, a shaft connected to the discs, means for advancing the shaft stepwise in opposite directions, said means including ratchet means on the shaft, a reciprocable member, a pair of pawl elements carried by the member and alternately engageable with the ratchet means, means for reciprocating the member, the pawl elements moving in unison and in the same direction with it, control means for controlling the action of the pawl elements on the ratchet means, and a pattern device for controlling the control means.

SAMUEL P. PARKER.
